UNITED STATES PATENT OFFICE

150,950

DESIGN FOR A HEATER

Frederick Donald Hart, Nashville, Tenn., assignor
to Tennessee Enamel Manufacturing Co., Nash-
ville, Tenn., a corporation of Tennessee

Application October 30, 1947, Serial No. 142,228

Term of patent 14 years

(Cl. D81—19)

To all whom it may concern:

Be it known that I, Frederick Donald Hart, a citizen of the United States, residing at Nashville, in the county of Davidson and State of Tennessee, have invented a new, original, and ornamental Design for Heaters, of which the following is a specification, reference being had to the accompanying drawing, forming a part thereof, wherein

Fig. 1 is a front elevational view of a heater, showing my new design;

Fig. 2 is a side elevational view of the heater shown in Fig. 1; and

Fig. 3 is a top plan view of the heater shown in Fig. 1.

The side of the heater, not shown, is substantially like the side shown in Fig. 2.

I claim:

The ornamental design for a heater, as shown and described.

FREDERICK DONALD HART.
